CLAIM

(21) Appl. No.: **29/457,089**

The ornamental design for a mobile application interface for display or portion thereof, as shown and described.

(22) Filed: **Jun. 6, 2013**

DESCRIPTION

(51) LOC (10) Cl. 14-04

FIG. 1 is a front view of a first embodiment of a mobile application interface for display or portion thereof of our new design.

(52) U.S. Cl.

FIG. 2 is a front view of a second embodiment of a mobile application interface for display or portion thereof of our new design.

USPC **D14/485**
CPC **G06F 3/04817** (2013.01)

FIG. 3 is a front view of a third embodiment of a mobile application interface for display or portion thereof of our new design; and,

(58) **Field of Classification Search**

FIG. 4 is a front view of a fourth embodiment of a mobile application interface for display or portion thereof of our new design.

USPC D14/485–495; 715/700–867, 973–977;
700/82, 276, 277; 236/18, 51, 94

The portions of the display screen, text, and other features depicted in broken lines are not part of the claimed design.

CPC G06F 3/0481–3/0486
See application file for complete search history.
